CLAIM

The ornamental design for a canine diaper harness, as shown and described.

DESCRIPTION

FIG. 1 is a top front perspective view of a canine diaper harness showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof; and,

FIG. 8 is a top rear perspective view thereof, shown in use. The broken lines shown in the drawings depict environmental structure that forms no part of the claimed design.
